Inventor,
Frank De Minico;
By Wilbur McStone
his Attorney.

UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

ADDRESSING MACHINE.

Application filed July 7, 1920. Serial No. 394,517.

To all whom it may concern:

Be it known that I, FRANK DE MINICO, a citizen of the United States, and a resident of New York, borough of Bronx, in the 5 county of Bronx and State of New York, have invented certain new and useful Improvements in Addressing Machines, of which the following is a specification.

This invention relates to addressing machines, and has for its object to provide means in a machine of the class specified for printing on certain of the articles addressed a character to indicate certain classifications of said articles, such as town 15 classification.

To these ends my improvements comprise features which are illustrated in their preferred embodiment in the accompanying drawings, and which are fully set forth in 20 this specification, wherein:

Figure 1 is a side elevation of so much of an addressing machine as will suffice to illustrate my improvements. Fig. 2 is a top plan view of what is shown in Fig. 1. Figs. 25 3 and 4 are side elevations similar to that of Fig. 1 and show steps in the operation of the machine. Fig. 5 is a perspective view of some of the details of the mechanism. All of the figures of the drawings except Fig. 30 5 are to one scale and the scale of Fig. 5 is much enlarged over that of the other figures.

The machine to which I have chosen to illustrate the application of my improvements is particularly adapted for printing 35 on the margin of a newspaper or other publication the address of the person for whom the paper is intended, from one of a series of plates having that address embossed thereon, and which series of plates are 40 hinged together into a chain of plates, and which chain and papers are fed through the machine and brought into coacting relation. Such a machine is set forth in my United States Patent No. 1,232,662 of July 10, 1917, 45 to which reference may be had.

Referring now particularly to Figs. 1 and 2 of the drawings herewith, a chain of address plates 2, comprising a plurality of individual, articulated plates, as 3, 4, 5, 50 each bearing on its outer face a suitable embossed address, not shown, but of a character well known in the art, is advanced so as to present each successive plate to printing position by means of drum 6 fixed to shaft 7. 55 This drum is rotated continuously through

reduction gearing from shaft 8 and which shaft makes one complete rotation for each incremental advance of drum 6. Below said drum, for supporting the articles to be printed, is table 9, and adjacent either 60 lengthwise edge of and just below which, are feed chains as 10. Said chains are provided with dogs 11, suitably spaced apart, lengthwise said chains and reaching upwardly to above the upper face of said table 65 for engaging and advancing said articles from right to left, Fig. 1. Said chains are advanced, by means not shown, a distance equal to the distance between two successive dogs 11, for each incremental advance of drum 6, and said chains are brought to rest or nearly to rest when they have delivered an article to printing position. Platen 12 rises for presenting each successive article 70 against its printing plate at suitable intervals of time, by means not shown herein, but fully shown in my above mentioned patent. Opening 13 in table 9 permits the passage of platen 12 to deliver the article 75 against the printing plate at printing position.

Directing attention now more particularly to the classification printing device, supplemental frames 15 and 16 are supported from main frame 14 by studs 17, 18 and pivoted for oscillation in said supplemental frames 80 is shaft 19. Fixed to shaft 19 is arm 20 connected by link 45 with the strap of eccentric 21 fixed to shaft 8. By this means, at each rotation of shaft 8 and at each incremental movement of plate chain 2, and at each incremental advance of articles, as 22, 23, shaft 19 is caused to oscillate back and forth. Hung by links 24, 25 to frame 16 is oscillating bar 26, and hung by link 27 to stud 17 is oscillating feeler 28. Said link 27 is connected to the adjacent end of oscillating bar 26 by link 29. Feeler 28 terminates in feeler blade 30 and the point of said blade is normally held up against the chain of plates by spring 33. For throwing said point of feeler blade 30 downwardly, out of contact with said chain of plates at predetermined times, roll 34 pivoted at 31 on feeler 28 engages cam 32 fixed 85 on stud 17. Oscillating bar 26 is normally urged toward the right against pin 36 in frame 16 by spring 35. Carried by oscillating bar 26 is classification printing head 37. Said head is vertically slidably mount- 90

ed and is normally urged upwardly away from the path of the articles by spring 38. For engagement with and adapted for forcing said head downwardly into contact with an article thereunder, when said head is in printing position, hammer 39 is provided. Said hammer is carried by arm 40 fixed to oscillating shaft 19. Also, downwardly projecting from the hub of arm 40 is trigger 41 adapted for engagement with latch 42 pivotally mounted in the left hand end of oscillating bar 26. Said latch is normally urged upwardly to engaging position by spring 43. For giving an initial movement to oscillating bar 26 to move that bar into position to be further moved by power, certain predetermined chain plates are provided with tongues 44, respectively, as shown on plates 3 and 4, and particularly in Fig. 5. Said tongue is in line, lengthwise the machine, with sharp lip 30^a at that end of feeler blade 30 which is normally held up by spring 33 against the chain of plates, Fig. 3. At either side of said lip 30^a, the nose of feeler blade 30 is rounded off, see Fig. 5, so that the joints of the plates in the chain will pass that nose without catching thereon.

It will be observed that the printing station for the classification printer 37 is some distance to the left of the address printing station, and this distance is for convenience equal to one increment of spacing of dogs 11, so that the two printings will be simultaneous. By this arrangement, plate 4, from which the address has been printed on article 23 also bears tongue 44, which through feeler blade 30, gives the indication for the operation of the classification printer. Address printer as 4 and classification printer 37 may be inked by some convenient means not shown.

The operation of my improved machine is as follows: The several parts of the machine being in the positions respectively shown in Fig. 3 and shaft 8 being in rotation in anti-clockwise direction, it will be observed that projection 44 of plate 4, from which plate the leading end of article 23 has just previously been printed, encounters lip 30^a of feeler blade 30. Said projection pushes that feeler blade, feeler 28 and oscillating bar 26 to the left to the positions, respectively, of Fig. 4. This brings latch 42 into the path of trigger 41 as that trigger is swung to the left by the oscillation of shaft 19, actuated by eccentric 21 on shaft 8. Said trigger thereupon takes up the work of moving bar 26 to the left by power and carries it to the position of Figs. 1 and 2, thereby bringing classification printer 37 into the path of the downward movement of hammer 39. Said hammer thereupon engages said printer 37 and presses it downwardly against the leading end of article 23 therebelow and im-

prints its character thereon, coincident with the printing of the address upon the leading end of the next succeeding article 22, see Fig. 1. Also, during the movement of the mechanism from the position of Fig. 4 to that of Fig. 1, roll 34 engages cam 32 and feeler blade 30 is thrown downwardly out of engagement with tongue 44 so that the chain of plates may proceed onwardly around drum 6.

If no tongue 44 is encountered by feeler blade 30, oscillating bar 26 remains at rest and trigger 41 swings to the right without engaging latch 42 and hammer 39 descends without engaging printer 37. In case bar 26 should be moved to the left a trifle late to get ahead of trigger 41, said trigger will descend onto said latch and temporarily depress it, until said latch advances sufficiently to catch up with and get ahead of said trigger. Upon the reverse oscillation of shaft 19, trigger 41 swings to the right, thus liberating bar 26 and feeler 29 and feeler blade 30, which are returned to the positions, respectively, of Fig. 3 by spring 35.

I claim:

1. In a machine of the class described the combination of a series of printing plates, means for advancing said plates serially to and away from printing position, a classification printer carrying a latch, a hammer for impressing said classification printer upon an article, a trigger carried by said hammer, and means carried by one of said printing plates for bringing said latch into the path of said trigger whereby said hammer is brought into operative relation with the classification printer.

2. In a machine of the class described the combination of a series of printing plates, means for advancing said plates serially to and away from printing position, a classification printer carrying a feeler and a latch, a hammer for impressing said classification printer upon an article, a trigger carried by said hammer, and means carried by one of said printing plates for engaging said feeler for bringing said latch into the path of said trigger whereby said hammer is brought into operative relation with the classification printer.

3. In a machine of the class described the combination of a series of printing plates, means for advancing said plates serially to and away from printing position, means for advancing articles to be printed to and away from said printing position, means for bringing an article and a plate into printing engagement, a classification printer carrying a latch, a movable hammer for impressing said classification printer upon an article, a trigger carried by said hammer, and means carried by one of said printing plates for bringing said latch into the path of said trigger whereby said hammer is brought

into coacting relation with the classification printer.

4. In a machine of the class described the combination of a series of printing plates, means for advancing said plates serially to and away from printing position, means for advancing articles to be printed to and away from said printing position, means for bringing an article and a plate into printing engagement, a classification printer, a movable member carrying a latch and the classification printer and a feeler, a movable hammer for engaging said classification printer, a trigger carried by said hammer for engaging said latch, means for moving said hammer, a tongue carried by one of said printing plates for engagement with said feeler whereby when said tongue engages said feeler the movable member is shifted to bring said latch into the path of the trigger whereby said trigger shifts said movable member to bring the classification printer into coacting relation with said hammer, and means for synchronizing the operations of the printing plate and the classification printer.

5. In a machine of the class described the combination of a series of printing plates, means for advancing said plates serially to and away from printing position, means for advancing articles to be printed to and away from said printing position, means for bringing an article and a plate into printing engagement, a classification printer, an oscillating bar carrying a latch and the classification printer, an oscillating shaft having fixed thereon a hammer and a trigger, a feeler operatively connected to said oscillating bar, a tongue carried by one of said printing plates for engagement with said feeler whereby when said tongue engages said feeler the oscillating bar is shifted to bring said latch into the path of the trigger whereby said trigger shifts said bar to bring the classification printer into coacting relation with said hammer, and means for synchronizing the operations of the printing plate and the classification printer.

6. In a machine of the class described the combination of a series of printing plates, means for advancing said plates serially to and away from printing position, means for advancing articles to be printed to and away from said printing position, means for bringing an article and a plate into printing engagement, a classification printer, a

movable member carrying a latch and the classification printer and a feeler, a movable hammer for engaging said classification printer, a trigger carried by said hammer for engaging said latch, means for moving said hammer, a tongue carried by one of said printing plates for engagement with said feeler whereby when said tongue engages said feeler the movable member is shifted to bring said latch into the path of the trigger whereby said trigger shifts said movable member to bring the classification printer into coacting relation with said hammer, means for synchronizing the operations of the printing plate and the classification printer, a fixed cam, and means carried by said feeler for engagement with said fixed cam for throwing said feeler out of engagement with the tongue after said tongue has shifted the latch into the path of said trigger.

7. In a machine of the class described the combination of a series of printing plates, means for advancing said plates serially to and away from printing position, a classification printer carrying a feeler and a latch, a hammer for impressing said classification printer upon an article, a trigger carried by said hammer, a tongue carried by one of said printing plates for engaging said feeler for bringing said latch into the path of said trigger whereby said hammer is brought into operative relation with the classification printer, a fixed cam, and means carried by said feeler for engagement with said fixed cam for throwing said feeler out of engagement with said tongue.

8. In a machine of the class described the combination of a series of printing plates, means for advancing said plates serially to and away from printing position, means for advancing articles to be printed to and away from said printing position, means for bringing an article and a plate into printing engagement, a classification printer, a feeler operatively connected with said classification printer, a tongue carried by one of said printing plates for engaging said feeler whereby said classification printer is shifted into operative relation with its impressing means, a fixed cam, and means carried by said feeler for engagement with said fixed cam for thereafter throwing said feeler out of engagement with said tongue.

In witness whereof, I hereby affix my signature this 2d day of July, 1920.

FRANK DE MINICO.
